(57) CLAIM

The new and ornamental design for a lighted knife handle, as shown and described.

DESCRIPTION

FIG. 1 is a perspective view of the lighted knife handle of the present invention, the knife blade depicted in broken lines and not forming a part of the claimed design;
FIG. 2 is a top plan view of FIG. 1;
FIG. 3 is a side elevational view of FIG. 1, with the opposite side being a mirror image;
FIG. 4 is a bottom plan view of FIG. 1;
FIG. 5 is a rear end elevational view of FIG. 1; and,
FIG. 6 is a front end elevational view of FIG. 1.
